CLAIM

The ornamental design for a capsule bed, as shown and described.

DESCRIPTION

FIG. 1 is a front perspective view of a capsule bed showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view along line 8-8; and,

FIG. 9 is a cross-sectional view along line 9-9.

(Continued)

The broken lines shown represent portions of the capsule bed and form no part of the claimed design.

1 Claim, 9 Drawing Sheets
